United States Patent Office.

EBENEZER HAWKINS, OF ISLIP, NEW YORK.

Letters Patent No. 98,691, dated January 11, 1870.

IMPROVEMENT IN PAPER-ENGINES.

The Schedule referred to in these Letters Patent and making part of the same.

To all whom it may concern:

Be it known that I, EBENEZER HAWKINS, of Islip, in the county of Suffolk, and State of New York, have invented a new and improved Paper-Engine; and I do hereby declare that the following is a full, clear, and exact description thereof, which will enable others skilled in the art to make and use the same, reference being had to the accompanying drawings, forming part of this specification, in which—

Figure 1 represents a vertical section of my improved paper-engine.

Figure 2 is a plan or top view of the same.

Similar letters of reference indicate corresponding parts.

This invention relates to certain improvements in the "beating-engine" used for the treatment of "half stuff," and has for its object to provide more rapid and continuous action than could be obtained in the ordinary oval vat and single cylinder.

The invention consists in the arrangement and use of an annular vat or cistern, together with two or more beating-cylinders, all arranged so as to produce continuous and rapid action.

A, in the drawing, represents an annular vat or cistern, made of wood or other suitable material, of suitable size.

In the circular space formed within it, is arranged

the vertical driving-shaft B, which, by means of gear-wheels, or other suitable connections, imparts motion to two or more horizontal radial shafts, C C, and to the cylinders D mounted thereon.

The cylinders D are of a similar construction as those in the ordinary paper-engines, and are provided with teeth or cutters, in the usual manner.

Under each cylinder is formed, upon the bottom of the vat, a breasting, E, which may contain the usual block with the stationary cutters, and which may be of the form shown in fig. 1, or of any other suitable shape.

By having the annular vat and two or more cylinders, the "stuff" will be kept in constant action, and will, in a very short time, be properly prepared, while, in the ordinary vats, it is not at all acted upon while passing through the outer channel of the vat.

Having thus described my invention, I claim as new, and desire to secure by Letters Patent—

A paper-engine, consisting of the annular vat A and two or more beating-cylinders D D, substantially as herein shown and described.

EBENEZER HAWKINS.
